Piker, Wyoming, Ohio

Application May 9, 1952, Serial No. 19,648

Term of patent 14 years

(Cl. D58—17)

To all whom it may concern:

Be it known that we, Petra Cabot and Herbert M. Piker, citizens of the United States, respectively, residing at New York, in the county of New York and State of New York, and Wyoming, in the county of Hamilton and State of Ohio, have invented a new, original, and ornamental Design for an Insulated Pail, of which the following is a specification, reference being had to the accompanying drawing, forming part thereof.

Fig. 1 is a front elevation of an insulated pail, showing our new design.

Fig. 2 is a side elevation of the insulated pail.

Fig. 3 is a top plan view of the insulated pail.

Fig. 4 is a bottom plan view of the insulated pail.

We claim:

The ornamental design for an insulated pail, substantially as shown.

PETRA CABOT.
HERBERT M. PIKER.
